Application filed August 15, 1932. Serial No. 44,607. Term of patent 14 years.

To all whom it may concern:

The figure is a plan view of a knitted fabric, showing my new design, the obverse side of the fabric being the same.

In the view the fabric is shown enlarged approximately one and one-half times actual size, but which in the reduction to patent size will show the fabric approximately actual size.

In testimony whereof I affix my signature.
